UNITED STATES PATENT OFFICE.

JAMES H. ALBRIGHT, OF LAURELTON, PENNSYLVANIA.

CULTIVATOR.

SPECIFICATION forming part of Letters Patent No. 428,711, dated March 18, 1890.

Application filed August 29, 1887. Serial No. 248,188. (No model.)

To all whom it may concern:

Be it known that I, JAMES H. ALBRIGHT, a citizen of the United States, residing at Laurelton, in the county of Union and State of Pennsylvania, have invented certain new and useful Improvements in Cultivators, of which the following is a specification, reference being had therein to the accompanying drawings.

10 My invention relates to improvements in cultivators of the class in which use is made of wheels, a wheel-frame, and a draft-frame for supporting the operative parts and adapted to have the driver either ride upon the machine or walk behind it.

One of the objects of the improvements is to provide a machine that can be readily guided by the driver either when riding or when walking.

20 Another object is to provide means for supporting the shovels or plows in such way that they shall be held down by one or more springs adapted to yield sufficiently to allow them to rise when encountering obstructions, 25 in conjunction with a rigid bar by which the operator can at option prevent them from rising—as, for instance, when working in hard ground.

The invention also relates to other matters, 30 which will be understood from the description given below in connection with the accompanying drawings.

Figure 1 is a longitudinal section of a cultivator embodying my improvements, it being taken on line α γ , Fig. 2. Fig. 2 is a bottom plan view of the machine, the drag-bars and shovels or plows being removed. Fig. 3 is a rear elevation of the frames and wheels. Fig. 4 is a front view of the frames, showing 40 the particular devices by which the drag-bars are supported. Fig. 5 is a plan view of the drag-bars and shovels when arranged in one of their positions. Figs. 6, 7, 8, 9, 10, 11, 12, 13, and 14 show some of the parts of the machine detached.

In the drawings, C C represent the wheels. A is the axle, and to this are secured the longitudinal bars or side pieces B B of the supporting-frame, these being connected at 50 the front end by the cross-bar B'.

D is the pole or tongue, which is secured to the axle and to the cross-bar B'.

A' A' are brackets or hangers secured to the under side of the axle and extending downward somewhat therefrom.

55 A² A² are the wheel-spindles, these being pivoted at a' to the said brackets A' in such way that the spindles can be turned relatively to the other parts.

The parts A A' A² B B' constitute the 60 wheel-frame or main supporting-frame, to which the draft devices are secured. These frames may be varied as preference or circumstances may dictate without departing from the essential features of the invention. 65

The machine is adapted to support the driver, there being a seat at T, held by the springs or seat bar or bars T', secured to the above-described frame-work. To enable the driver while in this seat to guide the machine 70 by shifting the spindles A², the latter are elongated inwardly and terminate in foot-pieces a, suitably shaped to fit the foot. By pressing upon one or the other of these foot pieces or rests a' the wheels may be so deflected as to cause the machine to turn to the right or to the left, as desired. The spindles are by means of pitmen or links S connected to a cross-bar P, which is pivoted to the tongue, 75 and it will be seen that if either of the spindles A² be pushed forward the other will be pushed backward by reason of the motion imparted through the last-described connecting devices. The movements of the spindles are limited by means of a stop device in the 80 form, preferably, of a guide loop or stirrup A³, the upper ends of which are secured to the axle. The spindles A² have anti-friction

85 rollers L' bolted to the spindles. These rollers bear upon the aforesaid stop device or guide-piece A³, and when they are employed the resistance to the movement of the spindles and 90 wheels is reduced to such an extent that they can be readily turned into the desired position.

95 The steering of the machine can be effected by hand whenever necessary or desired, for I employ also a lever H and pivot it at h to a bracket fastened to the axle. This lever is connected with the cross-bar P by link or pitman S', and by drawing it back or thrusting it forward the driver can while in his seat 100 change the direction of the machine. This can be used independently of the foot-steer-

ing device and in conjunction therewith—as, for instance, when the wheels are so situated as to resist movement under such force as can be brought to bear through the driver's foot. 5 These steering devices can also be brought into operation when the driver is walking, there being combined with them, also, a hand-lever I , pivoted to the central part of the axle, and extending backward, preferably, to points 10 somewhat behind the driver's seat. It is projected forward a short distance and also laterally from its main longitudinal line, as clearly shown at i , Fig. 2. This part i is connected by a link or pitman S^2 with the aforesaid pivoted cross-bar P . By throwing lever I to the right or left the spindles and wheels 15 will be turned in such way as to change the direction of the machine. The link or pitman S^2 can be joined to the cross-bar P on either 20 side of the pivot of the latter, according to the direction of motion desired.

The cultivating devices proper are constructed and attached as follows: N are strong irons firmly secured to the front of the 25 frame B B' , there being braces W' , which are secured to their lower ends, and are also fastened to the bars B at points in the rear.

M M represent metal bars, which extend downward from the front cross-bar B' , they 30 being secured to the latter by eyebolts m , so as to be free to move when desired. At the lower ends of these bars braces W are connected, which extend backward and upward to suitable fastening devices at W^4 on the 35 axle, there being jam-nuts by which these braces and bars M can be drawn into the desired position and then firmly clamped. The braces W W' and the vertical bars M N are joined together by means of the rods R^5 , which 40 support the drag-bars, these rods being shouldered and provided with pins or nuts for firmly securing the parts together.

W^3 W^3 represent supplemental braces, each of which is at one end fastened to one of the 45 vertical bars N and at the other end is fastened to the cross-bar B' by one of the aforesaid eyebolts m . Upon these parts the drag-bars are supported, they consisting of a main drag-bar R , together with supplemental bars 50 R' R^2 R^3 . These are preferably made of flat iron, and in order to secure them firmly to the supporting-rods R^5 and give them as wide a base of connection as possible I employ a supplemental bar R^4 , which is joined to the rod R^5 55 at one end, the bar R being joined to said rod at the other. The bars R R^4 are bent and provided with eye-pieces at their ends, which are transverse to the rod R^5 , and the eyes in these parts fit the reduced portions of the rods R^5 , 60 so that they can bear against the shoulders on the larger parts; hence they are kept separate notwithstanding the great strain that is brought to bear upon them. The bars R' , R^2 , and R^4 are bolted to the central drag-bar 65 R , and the bar R^3 is bolted to the bar R^2 . To these drag-bars the shovels or plows are attached, the latter being of any preferred kind

and secured in any suitable way. I prefer to employ fenders such as shown at R^7 , they being also bolted to the drag-bar frame. The 70 drag-bars themselves can be also modified in construction; but I prefer to make them in the way shown and above described, as I thereby provide a light, strong, and durable framework for carrying the shovels. 75

The rear portion of each shovel-frame is supported from the wheel-frame as follows: R^6 is a cross-bar for connecting the drag-bars of each shovel-frame, it being formed or provided with downwardly-projecting slotted 80 arms r' , by which each of the drag-bars can be adjusted vertically independently of the others. At the center it has an eye r^2 , to which is loosely connected a supporting-rod V , there being one of these supporting-rods V 85 on each side of the machine—one for each shovel-frame. These rods V pass upward through guide-pieces V' , each having a perforated ear v at the bottom and a perforated top piece v' . 90

V^2 is a spiral spring placed around the rod V , the ends of the spring bearing, respectively, against the ears or plates v v' . The rod V projects through the perforated plate v' , and is provided with a nut v^3 , by which a 95 positive bearing can be obtained.

K is a rock-shaft mounted in bearings on the wheel-frame, it having arms K^2 , which are pivotally connected with pins or studs V^4 , formed with guide-pieces V' . When the parts 100 are in position, it will be seen that the shovels can be lowered by turning the lever K' backward, and that the shovels can be held down under the force of the springs V^2 if the lever K and arms K^2 are turned backward 105 sufficiently to force the guide-pieces V' down upon the rods V . When the parts are so arranged, the shovels can rise to pass obstructions, and at the same time will be held with sufficient pressure for ordinary work. When 110 it is desired to lift the shovels out of operation, lever K' is thrust forward, which elevates the guide-pieces V' until plates v' come into contact with the nuts or stops v^3 , after 115 which the shovels will be positively elevated. 120

Under some circumstances it is desirable to hold the shovels down to their work rigidly and positively, in contradistinction to holding them under spring-pressure, as above described. This can be accomplished by placing stops above the rods V , or otherwise positively locking the said rods relatively to the 125 guide-pieces V' . As shown, the latter are formed with upwardly-projecting perforated ear-pieces v^4 , adapted to receive bolts V^3 directly above the upper ends of the rods V . When these bolts are interposed, the rods cannot rise and the shovels will be held down rigidly.

What I claim is—

1. In a cultivator of the character described, the combination, with the wheels, the axle, and the draft-frame, of the two independent shovel-frames adapted to lie one on one side 130

and the other on the other side of a row of plants, the downwardly-projecting supporting-bars M, the pivots R⁵, the rock-shaft K, mounted directly upon the axle, the lever K', secured directly to the rock-shaft K, the cross-bar R⁶, secured to each shovel-frame, rod V, guide V', hinged to the rock-shaft, the springs V², and the removable stop for rigidly connecting the parts V and V', substantially as set forth.

2. In a cultivator of the character described, the combination of the wheels, the axle, the angular brackets A', extending downward from the axle, the pivoted spindles for the 15 wheels, the pivot-bolts a', passing through the bases of the brackets and through the wheel-spindles, the loops A³, secured to and depending from the axle and surrounding the wheel-spindles, and the rollers L', secured to 20 the wheel-spindles and bearing against said loops, substantially as set forth.

3. In a cultivator of the character described, the combination of the wheels, the axle, the frame B B, secured to the axle, the cross-bar 25 B' in front of the axle, the bars M, depending from the frame, the shovel-frames pivoted to the bars M and extending to a point behind the axle, the vertical lifting-rods V, pivoted

to the shovel-frames, the adjustable cross-bar R⁶, the rock-shaft K, mounted upon the axle, 30 the lever K', the arms K², secured to the rock-shaft and projecting rearwardly from the axle, the guide V', and the spring V², substantially as set forth.

4. The combination of the wheels, the axle, 35 the draft-frame, the pivoted wheel-spindles, the shovel-frames hinged independently of each other, the lifting devices V V', the rock-shaft, the lever K', the vertically-arranged lever H, the swinging bar P, connected to the 40 wheel-spindles, and the horizontally-arranged lever I, also connected to the vibrating bar P, substantially as set forth.

5. In a cultivator of the character described, the combination of the wheels, the axle, the 45 pivoted wheel-spindles, the loops A³, having a cross-bar below the spindles and a cross-bar above the spindles, and the rollers L', secured to the spindles and bearing upon the lower cross-bars, substantially as set forth. 50

In testimony whereof I affix my signature in presence of two witnesses.

JAMES H. ALBRIGHT.
